(57) **CLAIM**

The ornamental design for an electrical connection terminal, as shown and described.

DESCRIPTION

FIG. 1 is a front elevational view of an electrical connection terminal showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a perspective view showing a front, top and right side thereof;

FIG. 8 is a perspective view showing a rear, bottom and left side thereof;

FIG. 9 is a perspective view showing a front, right side and bottom thereof; and,

FIG. 10 is a perspective view showing a rear, left side and top thereof.

The broken lines are shown for environmental purposes only and depict portions of the electrical connection terminal that form no part of claimed design.

1 Claim, 9 Drawing Sheets
